[57] **CLAIM**

The ornamental design for a disposable telephone handset cover, as shown and described.

DESCRIPTION

FIG. 1 is a top plan view of a disposable telephone handset cover embodying my design, the bottom plan view being a mirror image thereof, and with the broken lines representing stitching;

FIG. 2 is a left side elevational view of the handset cover as seen in FIG. 1, the right side being a mirror image thereof and with the broken lines representing stitching;

FIG. 3 is a front elevational view of the handset cover as shown in FIG. 1;

FIG. 4 is a rear elevational view thereof with the broken lines representing stitching; and,

FIG. 5 is a top perspective view of the handset cover as shown in FIG. 1 with a telephone handset positioned therein. The broken line showing of the telephone handset is for illustrative purposes only and forms no part of the claimed design.

The patterned surface treatment schematically depicted throughout the views is continuous about the surfaces at each end of the transparent center portion of the cover.
